GERARD DE P. BENNET, OF BROOKLYN, NEW YORK, ASSIGNOR TO HOLLAND SPRINKLER COMPANY, INC., OF NEW YORK, N. Y.

FUSIBLE LINK FOR SPRINKLER-HEADS.

1,113,596.

Specification of Letters Patent. Patented Oct. 13, 1914.

Application filed May 20, 1914. Serial No. 838,832.

To all whom it may concern:

Be it known that I, GERARD DE PEYSTER BENNET, a citizen of the United States, residing at Brooklyn, in the State of New York, have invented a new and useful Fusible Link for Sprinkler-Heads, of which the following is a specification.

My invention relates to an improvement in fusible links for sprinkler heads, and particularly such as are used in devices for automatically extinguishing fires, in which the fusible link comprises a plurality of members secured together by means adapted to be loosened upon a rise in temperature of a predetermined degree and adapted to be secured in a frame between a water closure and means for applying pressure to the link; and is a modification of the device disclosed in my application filed March 14, 1914, and serially numbered 824651, and is adapted to be used in connection with such sprinkler head as is illustrated therein. Heretofore in devices of a similar nature the parts have either been multiplied unnecessarily, or were not efficiently and compactly arranged, or have been complicated and uncertain in their action besides being more or less difficult to adjust; and have been to a greater or less degree liable to premature disintegration because of the creeping of the uniting medium under the strain of compression, in my devices I have overcome these objections.

The objects of my improvement are:— First, to provide a simple, cheap, compact and reliable fusible link. Second, to provide such a link as will be fully protected by and be entirely within the lines of the yoke or frame. Third, to eliminate from the complete sprinkler head all artificial springs or auxiliary devices for separating the component parts of the link. Fourth, to provide a fusible link which shall securely hold the water closure until released by a rise in temperature sufficient to cause the separation of the component parts of the link. Fifth, to provide a device which shall be positive and reliable in its action and secure against premature release and separation. I attain these objects by the means illustrated in the accompanying drawings, set out in the following description, and claimed herein.

In the drawings like symbols of reference

refer to like parts throughout the respective views.

In the drawings Figure 1 is a side elevation of my improved link ready for insertion in the sprinkler head. Fig. 2 is a side elevation of the link, assembled, but before the solder is applied to unite the parts. 58 Figs. 3 and 4 are perspective views of various parts of the link before assembly. Fig. 5 is a side elevation of the link showing its disintegration when the binding medium has sufficiently softened to release the 60 component parts.

In the figures, 1 represents one of the members comprising a part of the link.

2 represents the other member, 3 is a shoulder on the member 2 against which the lower edge of the member 1 abuts and on which it is supported, 4 is a shoulder or seat at the end of the member 1 opposite to the part which abuts against the shoulder 3 and which is adapted to be engaged by a 70 compressing screw in the sprinkler head frame; 5 is a knife edge on one end of the member 2 adapted to engage and preferably to fit into a slot in the water closure forming a part of the sprinkler frame (as the sprinkler frame and water closure are well known devices and are particularly illustrated in my application above mentioned they are not further illustrated or described herein).

6 is a shoulder or ledge depending from 85 the top of the member 1 so as to form a lock as hereinafter described; 7 is a lock plate fitting preferably in a groove 8 in the member 2 and projecting upward sufficiently to lie in the recess in the member 1 formed 90 by the shoulder 6.—

It has been found that for some purposes and on some occasions it is desirable that the adjoining or contiguous faces of the parts of the link be relatively smooth and 95 flat. The two contiguous faces are adapted to be secured together preferably by means of soft solder of such a composition that it will melt at a comparatively low predetermined temperature. If, however, the soft 100 solder alone be relied upon to join and hold the component parts of the link in position it has been found that that will be insufficient, as a sliding action under compression will take place, and the parts will separate 105 even without the application of heat, there-

fore I provide the shoulder 3 against which I abut the member 1 by which means I prevent the sliding effect while yet obtaining a structure which is easily separated into its 5 component parts upon a sufficient rise of temperature.

It will be further observed that by placing the knife edge on one side of the line of separation of the parts, or the medial line 10 of the link, I secure an unstable strut so soon as the binding medium is softened, so that the greater the compression of the sprinkler head screw, or the greater the pressure of the water against the closure and hence against 15 the engaging knife edge of the link, so much the greater is the leverage and so much more sure is the resulting separation of the parts. It will be seen therefore that as soon as the solder is melted or sufficiently softened, the 20 members 1 and 2 being under a high degree of compression, as is well understood in the art, will, because of their shape and arrangement relative to the screw and closure to the sprinkler head, tend to part and spring 25 asunder so as to invariably unseat the water closure, whereupon the usual operation of the sprinkler is performed. It has been found however that when the compression is greatly increased as is the present practice,—even the provision of the shoulder 3 may be insufficient to insure stability of the 30 strut until the temperature rises sufficiently to soften the solder,—I therefore have provided a locking device which insures security 35 from premature disintegration and yet permits operation at the proper time.

The lock plate 7 is soldered into the slot 8 so that the end which projects above the top of the member 1 forms the short end of 40 a lever the fulcrum of which is at 9 Fig. 5 and the long arm is firmly held by the solder in the slot 8. It is evident that even if the pressure is sufficient to cause the solder uniting the faces of the members 1 and 2 at 10 45 to creep or stretch,—yet so long as the lock plate 7 remains in place in the slot 8 and behind the shoulder 6,—disintegration of the link cannot take place,—and it is found that the binding effect of the solder on the 50 long arm of the lock plate 7 in the slot 8 is amply sufficient to maintain the plate in position, and consequently the stability of the strut,—while a rise in temperature sufficient to soften the solder between the members 1 and 2 at the faces 10 will also release the 55 lock plate 7 from the groove 8 and thus permit the collapse of the whole link as illustrated in Fig. 5 and result in the operation of the sprinkler.

60 It will be understood that I do not limit myself to any particular shape or proportion or material, though I have illustrated herein

what I consider to be the desirable embodiment of my invention. But

What I claim is,—

65 1. A fusible link comprising a plate of substantially the same length as width, having a knife edge at one end to one side of the medial line, a shoulder directly above said knife edge and parallel therewith, and a longitudinal recess in the outside face; a second member of substantially the same size provided with a knife edge at one end adapted to bear against the shoulder of the first member, a seat at the other end adapted to 70 be engaged by a compressing member of a sprinkler head frame, and having a recess extending across the inside face; a locking member adapted to fit into the longitudinal recess of the first member and having one 75 end projecting into the recess in the second member, the contiguous faces of the three members being joined and the recesses and the intermediate spaces being filled with an easily fusible medium, substantially as de- 80 scribed.

85 2. A fusible link comprising a member one end of which is adapted to engage a pipe closure and having a longitudinal recess in its outside face; a second member of substantially the same size adapted to be supported by the first member and to be engaged by a sprinkler head frame, and having a portion overhanging the first member; a third member lying in the longitudinal 90 recess of the first member and engaging the overhanging portion of the second member; the first member being joined to the second member, and the third member to the first by an easily fusible medium, substantially as described.

95 3. A fusible link comprising a rigid member one end of which is adapted to engage a pipe closure and having a longitudinal recess in its outside face; a second rigid member of substantially the same size engaging the first member and adapted to be engaged by a sprinkler head frame, and having a portion overhanging the first member; a third member lying in the longitudinal recess of 105 the first member and projecting within the overhanging portion of the second member; the first member being joined to the second member and the third member to the first by an easily fusible medium which fills up 110 the interstices between the first and third members, and between the first member and the overhanging portion of the second member.
